UNITED STATES PATENT OFFICE.

JOHN E. GARDNER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 7, 1922, Serial No. 541,780. Renewed August 12, 1926.

The present invention relates in general to automatic telephone systems, but is more particularly concerned with small automatic exchange systems of a type which have come into extended commercial use in manufacturing plants, mercantile establishments, and the like.

More specifically, the present invention is concerned with small private automatic exchange systems of one hundred lines or less in which each subscriber has an individual line switch which has access to local connector switches of a new design, and the general object of the invention is to arrange the circuits of a system of this character so that it may be readily enlarged to accommodate additional lines with little or no change in the existing equipment, and with the addition of but another group of connector switches. Heretofore, in order to increase the size of a one hundred line connector system the ordinary method involved the installation of selector switches and a change in the trunking of the existing equipment so that the subscribers' line switches, instead of having direct access to the connector switches, had access to selector switches, these selectors in turn having access to two groups of connector switches. The present invention provides novel circuit arrangements for accomplishing the same results without the addition of selector switches. It is, of course, obvious that the scheme used herein may be installed originally if a system larger than 100 lines is desired.

There are other objects of the invention not now specifically mentioned, which, together with the foregoing will be described hereinafter, reference being had to the accompanying drawing forming part of this specification.

Referring now to the figure of drawing, there is shown by means of the conventional circuit diagrams enough of the apparatus to illustrate the invention. This includes a calling substation A, a line switch C, a connector H and a called substation A'.

The subscribers' substation A is of the ordinary automatic type, having the usual talking instrumentalities, and in addition an automatic calling device S. The line of the substation A terminates at the exchange in

an individual line or trunk selecting switch C.

The line switch C is of the usual rotary type, whose wipers are always in engagement when idle with the bank contacts associated with the trunk line last used. The line switch C, in common with a plurality of other line switches, has access to trunk lines leading to local connector switches, one of the latter being shown at H.

The connector H is similar to the usual Strowger switch of the vertical and rotary type. However, this connector differs from the ordinary construction in that it is provided with an extra level of bank contacts, making all together a total of eleven levels instead of ten. The connector is so arranged that its wipers are always standing opposite the first level of bank contacts which is thus a kind of normal level. The connector H has access to local subscribers' line, the substation associated with one of these being shown in the drawings at A'.

Relays such as 51 and 52 are slow to release, this being indicated by the cross hatching on their cores. Relays such as 14 and 162 are both slow to pull and slow to release, these relays being distinguished from the former type by showing the ends of the cores in solid black.

The line of the substation A' terminates at the exchange in the individual line switch C' which is similar to the line switch C, already described.

In order to describe the present invention it will be assumed that the private automatic exchange system about to be described has a capacity of ninety lines and it is desired to increase it to a larger system of 180 lines. It will be assumed further that this private automatic exchange has trunk lines leading from it to a main automatic exchange, so that subscribers in the private automatic exchange may extend calls to subscribers in the main automatic exchange. We will first consider the ordinary operation of the system before it is enlarged. In order to do this the manner in which a call is extended from the subscriber at the substation A to the subscriber at the substation A' will first be described. To extend a call to the substation A' the subscriber at substation A will remove his receiver and oper-

ate his calling device for the two digits which constitute the number assigned to the desired substation.

When the receiver is removed at substation A a circuit is completed over the line conductors 11 and 12 for the line relay 14 of the line switch C. Upon energizing, relay 14 at its armature 21 completes a circuit which includes the switching relay 15 and the motor magnet 16 in series, and at its armature 20 connects the test wiper 26 to the above circuit at a point midway between the switching relay and the said motor magnet. The operation of the line switch C now depends upon whether its wipers are associated with a busy trunk line or not. If the associated trunk line is busy there will be a ground potential present upon the test contact engaged by the test wiper 26, switching relay 15 will be short circuited, and the motor magnet 16, being supplied with direct ground by way of the said test wiper, will operate as a buzzer to advance the switch wipers 25-27, inclusive, step by step in search of an idle trunk line. However, in the present instance it will be assumed that when the receiver is removed at substation A the trunk line leading from the bank contacts associated with the wipers of the line switch C is idle, and it will be assumed further that this trunk line is the one shown in the drawing terminating in the bank contacts 30-32, inclusive. Under these conditions there will be no ground potential on the test contact 31 engaged by the test wiper 26, and the switching relay 15 will be energized immediately after the energization of the line relay 14. Relay 15, upon energizing, at its armature 18 places ground upon the test contact 31 to prevent the trunk line seized from being used for another call, and at its armatures 17 and 19 disconnects the line conductors 11 and 12 of the substation A from the winding of the line relay 14 and from ground, respectively, and extends them by way of armatures 17 and 19, wipers 25 and 27, bank contacts 30 and 32 to the upper and lower windings of the line relay 50 of the connector H.

The line relay 50 is immediately energized over the calling line loop and, upon operating, at its armature 65 closes the circuit of its associated slow-acting release relay 51. The latter relay, upon energizing, at armature 68 opens one point in the circuit of the release magnet, at the front contact of this armature prepares the impulsive circuits of the connector H, and at armature 67 places ground upon the release trunk conductor 49, thereby establishing a holding circuit for the line switch C. This holding circuit may be traced from ground on the release conductor 49 by way of test contact 31, test wiper 26, armature 18 and its front contact, through the winding of the switch-

ing relay 15, and thence through the winding of the motor magnet 16 to battery. This holding circuit serves to maintain the switching relay 15 energized throughout the connection and it will be understood that it is established before the slow-acting line relay 14 has had time to deenergize. A branch of this holding circuit extends by way of the private normal conductor 29 to multiple test contacts in the banks of the local connector switches such as H, whereby the line of the substation A is protected from intrusion during the existence of the connection.

The calling subscriber at substation A may now operate his calling device S for the first digit of the desired number thereby producing a series of interruptions in the circuit of the line relay 50. In response to the interruptions in its circuit the line relay deenergizes a plurality of times each time sending an impulse of current over the following circuit: ground by way of armature 65 and its back contact, armature 68 and its front contact, off normal springs 69 and 71, through the winding of the slow acting low resistance relay 52, and through the winding of the vertical magnet 60 to battery. The above is the circuit over which the first impulse is sent to the vertical magnet. However, upon the first vertical step of the switch shaft the off normal springs are shifted and the remaining vertical magnet impulses traverse a new circuit which is the same as the one previously traced except that it includes the off normal springs 69 and 70, and armature 75 and its front contact, the relay 52 being now in an operated position. Magnet 60 operates to raise the switch shaft carrying the wipers 112-114, inclusive, step by step until they are brought opposite the level of bank contacts corresponding to the digit dialed. The slow acting relay 52 is energized in series with the vertical magnet, maintains its armature attracted throughout the vertical movement of the switch and at the termination thereof deenergizes thereby transferring the impulsive circuit to the rotary magnet 62.

When the calling device at substation A is operated in accordance with the next and final digit of the desired number, another series of interruptions is produced in the circuit of line relay 50 thereby causing this relay to deenergize a corresponding number of times. At each retraction of its armature 65, an impulse of current is sent over a circuit extending from ground through armature 65 and its back contact, armature 68 and its front contact, off normal springs 69 and 70, armature 75 and its back contact, normally closed springs controlled by armature 88, armature 108 and its back contact, and thence through the winding of the rotary magnet 62 to battery. Rotary mag-

net 62 operates to rotate the switch wipers 112-114, inclusive, into engagement with the set of bank contacts associated with the line of the desired called subscriber at substation A', and which we will assume are the bank contacts 123-125, inclusive. The slow acting relay 57 is energized in multiple with the rotary magnet 62. Relay 57, upon energizing, at its armature 93 short circuits the springs controlled by armature 88 in order to preserve the continuity of the rotary magnet circuit while the switch wipers are being rotated over bank contact sets associated with busy lines, and at 15 its armature 92 connects the test wiper 113 to the test relay 56. The attraction of armature 91 of relay 57 is without function at the present time. The operation of the connector H now depends upon whether the 20 line of the substation A is busy or not.

It will first be assumed that the line of the substation A' is busy. Under these conditions there will be a ground potential present upon the test contact 124 engaged by the 25 test wiper 113. A circuit is thereupon completed extending from said grounded test contact by way of the said test wiper, normally closed springs controlled by armature 107, armature 92 and its front contact, armature 99 and its back contact and through the winding of the test relay 56 to battery. Relay 56 is immediately energized over this 30 circuit and, upon operating, at its armature 87 establishes a locking circuit for itself, at armature 88 opens the circuit of the rotary magnet 62, and at armature 89 connects a lead from the busy signalling machine to the lower heavy talking conductor. This tone is audible to the calling subscriber 35 at substation A who will replace his receiver as he knows that the called line is inaccessible at the present time. The replacement of the receiver at substation A causes the release of the connector H and line switch 40 C in a manner which will be described hereinafter.

It will now be assumed that the line of the substation A' is idle when the wipers of the connector H are rotated into engagement with the associated contact set comprising contacts 123-125, inclusive. When this occurs there will be no ground potential upon the test contact engaged by the test wiper 113 and the test relay 56 will not be 45 energized. Then, immediately following the deenergization of the slow acting relay 57, a circuit is completed which extends from ground on release conductor 49 by way of armature 87 and its back contact, through 50 the upper winding of the relay 59, through the upper winding of relay 58, back contact and armature 92, normally closed springs controlled by armature 107, test wiper 113, test contact 124, private normal conductor 55 163, through the winding of the switching

relay 160 of the line switch C', and thence through the winding of the motor magnet 161 to battery. Only the relays 59 and 160 are energized over this circuit. The relay 58 in the connector H is marginal and does 70 not energize in series with the windings of the switching relays of the line switches. The switching relay 160, of the line switch C, upon energizing, only partially attracts its armatures, that is enough to disconnect 75 the line of the substation A' from its normal battery and ground connections. This operation is brought about by a mechanical interlocking device controlled by the armature of the line relay 162.

In the connector H, the switching relay 59, upon operating, establishes a locking circuit for itself at armature 106, at armature 107 places ground upon the test contact 124 associated with the substation A' in order to 80 render the called line busy, opens the circuit of the rotary magnet 62 at armature 108 and at armatures 105 and 109 completes the signalling circuit. Ringing current from the generator Gen. is now intermittently projected out on the called line until an answer 85 is obtained.

When the called subscriber at substation A' removes his receiver a circuit is completed 90 for the ring cut-off relay 55. Upon energizing, this relay establishes a locking circuit for itself at armature 85, at armatures 84 and 86 opens the ringing circuit, and at the front contacts of these armatures finally 95 completes the talking connection. Conversation may now be carried on between the subscriber at substation A and the subscriber at substation A' over the heavy conductors, talking current being supplied to the calling 100 subscriber from the windings of the line relay 50 of the connector H and to the called subscriber from the windings of the impedance coil 53.

When the conversation is terminated both 105 the calling and the called subscriber will 110 replace their receivers upon their respective switch hooks. The release of the connection is brought about by the replacement of the receiver at substation A. When this receiver is replaced, the circuit of the line relay 50 is opened and this relay deenergizes thereby 115 opening the circuit of its associated slow acting release relay 51. Upon deenergizing, the latter relay at its armature 68 completes the circuit of the release magnet 61 of the connector H and at its armature 67 removes 120 ground from the release trunk conductor 49 thereby opening the holding circuit of the switching relay 15 in the line switch C. The release magnet 61, upon operating, restores 125 the connector H to normal position in the usual manner. The deenergization of relay 15 restores the line switch C to its normal condition.

The operation of the apparatus when one 130

subscriber in the private automatic exchange calls another party therein having been described, the operation when a connection is extended from a local subscriber to a called party in the main exchange will now be described. For this purpose it will be assumed that the subscriber at substation A desires to extend a connection to a subscriber in the main exchange. In order to do this the calling party will remove his receiver, operate his calling device for the digits 02 and thereafter the directory number of the desired subscriber in the main exchange.

15 When the receiver is removed at substation A the line switch C operates in the same manner as before described to select an idle trunk line and extend the calling subscriber's line thereover. It will be assumed that the 20 trunk line shown in the drawings extending to connector H is the one used. When the line of substation A is extended to the connector H the line relay 50 is immediately energized over the calling line loop and 25 operates to close the circuit of the slow acting release relay 51. The latter relay functions in the usual manner to prepare the impulsive circuits of the connector H and to place ground upon the release trunk conductor 49 thereby establishing a holding circuit for the line switch C. All the operations outlined above have already been described in the preceding connection and will be readily understood.

30 In response to the first operation of the calling device S at substation A the line relay 50 controls the operation of the vertical magnet 60 in stepping the switch shaft carrying the switch wipers 112-114, inclusive, 35 opposite the tenth level of bank contacts. When the switch wipers are brought opposite the tenth level, a cam on the switch shaft causes the shaft springs 80 and 81 to be forced into engagement with their working 40 contacts. By the operation of spring 81 a circuit is completed extending from ground through the winding of the relay 54, by way of spring 81 and its working contact and through the upper winding of the ring cut-off relay 55 to battery. Relay 55, upon attracting its armatures, establishes a locking 45 circuit for itself at armature 85, at armature 166 prepares a point in the locking circuit of the relay 54 and at armatures 84 and 86 50 prepares certain points in a repeating circuit which will be later described. Relay 54, upon operating, establishes a locking circuit for itself at armature 63, disconnects the battery and ground connections from the windings of the impedance coil 53 and connects the two windings in series across the talking conductors at armatures 82 and 83, thereby preparing another point in the previously 55 mentioned repeating circuit. The slow acting relay 52 maintains its armatures at-

tracted throughout the vertical movement of the switch and at its termination deenergizes preparing a circuit for the rotary magnet 62.

When the calling device at substation A is operated in accordance with the digit 2, two impulses of current are sent to rotary magnet 62. Magnet 62 operates to rotate the switch wipers into engagement with the second set of bank contacts in the tenth level. The slow acting relay 57 is energized in multiple with the rotary magnet and operates at its armature 92 to connect the test wiper 113 to the test relay 56 and at its armature 93 short circuits the springs controlled by armature 88 on the test relay. If the trunk line associated with the second set of bank contacts on the tenth level is busy ground will be connected to the test contact engaged by the test wiper 113 and test relay 56 will be energized. Upon energizing, relay 56 at armature 87 establishes a locking circuit for itself and at armature 88 completes the circuit of the rotary magnet 62 over a path extending from ground on release trunk conductor 49 by way of shaft controlled spring 80 and its working contact, resting contact of spring 73 and the said spring, back contact and armature 74, back contact and armature 96, armature 88 and its front contact, armature 108 and its back contact, and through the winding of the rotary magnet 62 to battery. Magnet 62 operates to rotate the switch wipers into engagement with the next set of bank contacts on the tenth level and at its armature 99 opens the locking circuit of the test relay 56. It will be noted that the slow acting relay 57 is maintained energized by a circuit in the multiple with the rotary magnet. Test wiper 113 is thus maintained in connection with the test relay 56. By the operation of the rotary magnet the circuit of relay 56 is opened and this relay deenergizes, opening the circuit of the rotary magnet, which deenergizes also. If the trunk line associated with the next set of bank contacts is busy, the relay 56 is again energized and operates, to close a locking circuit for itself and to complete the circuit of the rotary magnet 62. Magnet 62 operates, as before, to open the circuit of the test relay and to advance the switch wipers another step into engagement with the next set of bank contacts. The alternate operation of the relay 56 and the rotary magnet 62 continues until an idle trunk is found which we will assume is the trunk line shown in the drawings comprising conductors 149 and 142 and terminating in the bank contacts 118-120, inclusive. When the switch wipers are brought into engagement with this set of bank contacts there will be no ground connected to the test contact 119 and the test relay 56 will not be again energized. How-

ever, immediately after the deenergization of the slow acting relay 57 a circuit is completed which extends over the following path: ground on release trunk conductor 49 through armature 87 and its back contact, through the upper windings of the relays 59 and 58, back contact and armature 92, normally closed springs controlled by armature 107, test wiper 113, test contact 119, and 10 through the resistance R' to battery. On account of the marginal adjustment of relay 58 only the relay 59 is operated over the above circuit. Upon operating, the latter relay places ground upon the test contact 119, establishes a locking circuit for itself, and at armatures 105 and 109 places a bridge across the trunk conductors 140 and 142. This bridge may be traced from trunk conductor 140, by way of bank contact 118, 20 wiper 112, front contact and armature 105, armature 84 and its front contact, armature 91 and its back contact, through the upper winding of the impedance coil 53, armature 82 and its front contact, front 25 contact and armature 83, through the lower winding of the impedance coil 53, armature 66 of line relay 50 and its front contact, front contact and armature 86, armature 109 and its front contact, wiper 114, bank 30 contact 120, to trunk conductor 142. The above traced bridge or repeating circuit immediately causes the operation of the line relay in the incoming selector switch in the main exchange which closes the circuit of 35 its associated slow acting release relay. The latter operates to prepare the operating circuit of the incoming selector switch. The trunk comprising conductor 140 and 142 may terminate at the main exchange in a 40 line switch similar to the line switch C. This line switch, will then, of course have access to first selector switches in which case the bridge or repeating circuit previously traced, causes the operation of the line 45 switch in the main exchange to extend the connection to an idle first selector switch. In any event, in response to the digits of 50 the called subscriber's number, a series of selector switches and a connector switch are operated in the main exchange to extend the connection to the desired line. The impulses which control the switches in the main exchange are repeated by the connector H, as at each deenergization of the line 55 relay 50 in response to the operation of the calling device S the bridge across the trunk conductors 140 and 142 is opened at armature 66. It will be noted that during each 60 series of impulses the slow acting relay 57 is energized and maintains its armature attracted throughout the series. The operation of relay 57 serves to remove the impedance coil 53 from the bridge or repeating circuit and closes a direct bridge across the 65 trunk conductors 140 and 142 through the

armature 66 on the line relay 50. The operation of the automatic switches in the main exchange takes place in a well known manner.

When the conversation is terminated the 70 release of the connection is brought about by the replacement of the receiver at substation A in the usual manner.

The usual operations of the private automatic exchange system when a local call is 75 made and when a connection is extended to a subscriber in the main office having been described, the operation of the apparatus will now be described when the exchange is enlarged to take care of 180 lines. It is 80 necessary, in order to enlarge the private automatic exchange, to provide an additional group of line switches similar to line switch C so that each added subscriber's line may 85 terminate in one of these line switches. Another group of connector switches, similar to the connector switch H, will also be installed and made accessible to the added group of line switches by means of trunk lines in the same manner as the connector 90 H is accessible to the line switch C. In addition, in order to enable a subscriber, accessible to one group of connector switches, to call a subscriber accessible to the other 95 group of connector switches, the trunk lines leading to connector switches in one group are multiplied into sets of bank contacts in the normal level of bank contacts in the other group of connector switches. This is shown 100 in the drawings in connection with the connector H, the bank contacts 150-152, inclusive, being the set of contacts associated with the trunk line extending to the connector H in the normal level of the added group of connector switches. The trunk 105 lines leading to connector switches in the same group as is the connector H are multiplied in the normal level of the connectors in the other group in this same manner.

The connector switches in the group in 110 which connector H is located will, in the same manner, have access to trunk lines leading to the added group of connector switches. For handling outgoing connections more trunk lines to the main exchange may be installed and made accessible from the tenth level of the added group of connector switches, or if there are enough 115 trunk lines already accessible to the connector H and the other switches of its group to handle all the out going traffic of the new group of lines, the trunks accessible from the tenth level of the connectors such as H will be merely multiplied into the tenth level of the new group of connector switches.

In the enlarged system local connections 120 between subscribers in the same group and out going calls to the main office will be handled in the same manner as has already 125 been described. However, the operations 130

- of the connectors are somewhat different than have been previously described when the call is extended from a subscriber in one group to a subscriber in the other group.
- 5 In order to describe this operation, it will be assumed that the subscriber at substation A desires to call a subscriber whose line is accessible to the other group of connector switches. To accomplish this result the subscriber at substation A will remove his receiver, operate his calling device S for the digits O1 and thereafter the two digits of the local subscriber's number in the other group.
- 10 15 When the receiver is removed at the calling substation A, the line switch C operates in the same manner as before described to extend the calling subscriber's line over a trunk line to an idle connector switch. It
- 20 25 30 will be assumed that the trunk line shown in the drawings is the one selected by the line switch C. Immediately upon the extension of the calling subscriber's line, the line relay 50 of the connector H is energized and operates to close the circuit of the slow acting relay 51. The relay 51 operates to prepare the impulsing circuits of the connector H and to place ground upon the release trunk conductor 49. This latter operation serves to establish a holding circuit for the switching relay of the line switch C in order to maintain the said relay energized throughout the connection.

35 In response to the operation of the calling device S for the digit O the line relay 50 controls the operation of the vertical magnet 60 in raising the switch shaft carrying the switch wipers 112-114, inclusive, opposite the tenth level of bank contacts. When 40 the wipers are brought opposite the tenth level, the shaft controlled springs 80 and 81 are operated into engagement with their working contacts and the relays 54 and 55 are energized as before and with the same 45 results.

When the digit 1 is dialed, one impulse of current is sent to the rotary magnet 62 and the switch wipers are brought into engagement with the first set of bank contacts on the tenth level which are shown in the drawings at 115-117, inclusive.

The test contact 116 associated with this set of bank contacts is connected to battery through the low resistance R. Now, 55 immediately upon the deenergization of the slow acting relay 57, which is energized in multiple with the rotary magnet, a circuit is completed for the upper windings of relays 58 and 59.

60 Due to the low resistance of R as compared with the resistance of the switching relays of the line switches and resistances such as R', the marginal relay 58 is energized in series with the relay 59. Relay 58, 65 upon operating, establishes a locking circuit

for itself to ground through off normal spring 72 and its working contact at armature 95, at armature 98 closes the circuit of the relay 56 and at armature 94 opens a point in the locking circuit of the switching relay 59. Further results of the operation of relay 58 are that at armature 96 a point in the circuit of the rotary magnet 62 is opened and at armature 97 a circuit is closed for the release magnet 61. As the locking circuit of relay 59 is opened at armature 94 this relay does not remain energized. Relay 56, upon operating, opens the circuit of the upper windings of the relays 58 and 59 at armature 87, at the front contact of this armature establishes a locking circuit for itself, and at armature 88 prepares the circuit of the rotary magnet 62. The release magnet 61 of the connector H operates to restore the switch shaft carrying the switch wipers to normal position thereby bringing the said wipers opposite the normal level of bank contacts. When the switch shaft reaches its normal position the circuit of the release magnet 61 is opened as is the locking circuit of the relay 58 at the off normal springs. The latter relay deenergizes and at its armature 98 opens the original energizing circuit of the relay 56, at armature 97 opens another point in the circuit of the release magnet, at armature 94 prepares a point in the locking circuit of the switching relay 59, and at armature 96 completes a circuit for the rotary magnet 62 over the following path: ground by way of off normal spring 72 and its resting contact, resting contact of spring 73 and the said spring, back contact and armature 74, back contact and armature 96, armature 88 and its front contact, armature 108 and its back contact, and thence through the winding of the rotary magnet 62 to battery. The rotary magnet operates to rotate the switch wipers into engagement with the first set of bank contacts on the normal level and at its armature 99 opens the locking circuit of the relay 56. Relay 56, upon retracting its armatures, opens the circuit of the rotary magnet which immediately deenergizes. It will be observed that the slow acting relay 57 is energized in multiple with the magnet 62 and operates to connect the test wiper to the test relay 56. Upon the first rotary step of the switch shaft, the rotary off normal spring 66 is caused to engage its working contact thereby preparing a circuit for the release magnet 61. If the first trunk line on the normal level extending to connector switches, in the other group is busy, there will be a ground potential present upon the test contact engaged by the test wiper 113 and the test relay 56 will be immediately energized. As before, relay 56 operates to establish a locking circuit for itself and to close the circuit of the

rotary magnet. Magnet 62 advances the switch wipers into engagement with the next set of bank contacts and opens the circuit of the relay 56 which deenergizes opening 5 the circuit of the rotary magnet which deenergizes also. The alternate operation of the relay 56 and rotary magnet 62 continues until the switch wipers are brought into engagement with a set of bank contacts associated with an idle trunk line extending to a connector switch in the other group. It will be assumed that the trunk line shown in the drawings terminating in bank contacts 128-130, inclusive is the one selected by the 10 connector H. When the switch wipers are rotated into engagement with this set of bank contacts, there being no ground potential present upon the test contact 129, test relay 56 is not again energized and the rotation of the connector H ceases. Then, upon the deenergization of the slow acting relay 57, a circuit is closed for the switching relay 59 over the following path: ground on release trunk conductor 49 by way of armature 87 and its back contact, through the upper windings of relays 59 and 58, back contact and armature 92, normally closed springs controlled by armature 107, test wiper 113, test contact 129 to release trunk 25 conductor 136. Release trunk conductor 136 extends, in the same manner as the release trunk conductor 49, through an armature and back contact on the slow acting relay in the selected connector switch and through 30 a resistance such as R^2 to battery. The resistance R^2 is sufficiently high so that the relay 58 is not energized though the switching relay 59 is operated. Upon operating, relay 59 establishes a locking circuit for 35 itself at armature 106, at armature 108 opens the circuit of the rotary magnet, at armature 107 places direct ground on the release trunk conductor 136, and at armatures 105 and 109 closes a repeating circuit for controlling the 40 line relay of the seized connector switch in the other group. It will be noted that the relays 54 and 55 remain energized even after the operation of the release magnet 61 as ground has not been removed from the release trunk conductor 49. The repeating circuit above referred to may be traced from the trunk conductor 137, bank contact 128, wiper 112, front contact and armature 105, armature 84 and its front contact, armature 45 55 60 65 with the digits of a called number to connect with one of said telephone lines, and means automatically operative responsive to an operation of said switch in accordance with a predetermined number for releasing said switch and for causing it to select an idle one of said trunk lines.

2. In a telephone system, an automatic switch, telephone lines accessible to said switch, means for seizing said switch and for operating it only in accordance with two digits of a called number to connect with one of said telephone lines, means automatically operative if said switch is operated in accordance with a predetermined two digits for causing its release, and other telephone lines accessible to said switch in its vertically released position without calling any additional digits.

3. In a telephone system, a telephone line, an automatic switch, trunk lines accessible to said switch, means for connecting said line and said switch, releasing means for said switch to restore it to normal after it has been operated, a calling device on said line, means for operating said switch in response to two operations of said calling device before operating said releasing means, and means then automatically operative for causing the operation of said releasing means and for initiating the trunk selecting operation of said switch.

4. In a telephone system, an automatic switch, trunk lines accessible to said switch, means for seizing said switch and for operating it in accordance with a digit of a called number, means operative if said switch is operated in accordance with a predetermined digit for restoring it to normal, and means operative when said switch reaches its normal position for automatically causing it to select an idle one of said trunk lines.

5. In a telephone system, an automatic switch trunk lines and telephone lines accessible to said switch, divided into groups, means for seizing said switch and for operating it in accordance with a digit of a called number in one plane to select a group of said telephone lines and in accordance with another digit of said called number in another plane to select a line in a group, and means operative if the second digit corresponds to a predetermined one for restoring said switch to its initial position and for causing it to automatically select an idle one of said trunk lines.

6. In a telephone system, two groups of connector switches, a normal level of bank contacts for every connector in each group, a wiper set for each switch normally associated with its normal level of bank contacts, and trunk lines connecting the bank contacts of said normal levels with the connectors of the other group.

7. In a telephone system, two groups of

connector switches, telephone lines accessible to the connector switches of each group, means for seizing a connector in one of said groups and for operating it in accordance with the digits of a called number to connect with the corresponding accessible telephone line, trunk lines accessible to each group of connectors leading to switches in the other group, means operative only if a certain number is called for releasing said switch after the same is operated and for then causing the switch to elect an idle one of said trunk lines leading to a connector in the other group, and means for then operating the seized connector to extend a connection to one of said telephone lines.

8. In a telephone system, two groups of connector switches, telephone lines accessible to each group of connectors, a normal level for every connector in each of said groups, trunk lines extending from the normal levels of the connectors of one group to the connectors of the other group, and means controlled from one of said telephone lines for seizing a connector switch of one group and for operating it as a connector to connect with one of said accessible telephone lines or as a selector on its normal level to extend a connection to an idle connector in the other group.

9. In a telephone system, two groups of connector switches, telephone lines accessible to each group of connectors, a normal level for every connector in each of said groups, trunk lines extending from the normal levels of the connectors of one group to the connectors of the other group, means controlled from one of said telephone lines for seizing a connector switch of one group and for operating it as a connector to connect with one of said accessible telephone lines or as a selector on its normal level to extend a connection to an idle connector in the other group, and means for then operating the seized connector to extend the connection to one of said accessible telephone lines.

10. An automatic switch having directive movement and an automatic hunting movement, both starting from normal position, and means responsive to a directive movement of predetermined extent for restoring the switch and starting the hunting movement.

11. In combination, an automatic switch, trunk lines accessible to said switch, means for operating said switch, and means responsive only to an operation of predetermined extent for releasing said switch to normal and for causing it to automatically select an idle one of said trunk lines.

12. An automatic switch having bank contacts and wipers normally dissociated therefrom, bank contacts with which said wipers are normally associated, means for advanc-

ing said wipers to any desired set of normally dissociated bank contacts, and means responsive only to the advance of said wipers to a particular set of such contacts for 5 restoring said wipers and for advancing them automatically over the normally associated bank contacts.

13. In a telephone system, an automatic switch, trunk lines divided into two groups 10 accessible to said switch, means for seizing said switch and for directly controlling its operation to associate it with one of said groups of trunk lines, releasing means for said switch, means operative if a certain 15 predetermined digit is sent to said switch for initiating a trunk selecting operation in the group with which it is associated, and means operative if a different predetermined digit is sent to said switch for operating 20 said releasing means and for causing said switch to select a trunk line in the other group.

14. In a telephone system, an automatic switch, trunk lines accessible to said switch 25 divided into groups, means for seizing said switch and for operating it in accordance with a digit of a called number in one plane to associate it with a group of said trunks and in accordance with another digit of said 30 called number in another plane for causing

it to automatically select an idle trunk in said group of trunks, and means operative if the second digit corresponds to a predetermined one for restoring said switch to its initial position and for causing it to 35 automatically select an idle trunk in another group of trunks.

15. In a telephone system, a trunk line, other trunk lines, a directive device operable over said first trunk line and having a 40 normal position, and means responsive to a directive movement of said device of a predetermined extent for releasing said device and for automatically connecting said trunk line to an idle one of said other trunk 45 lines.

16. In a telephone system, an automatic switch having wipers, groups of lines accessible to said switch, means responsive to the dialing of a digit of a called number for 50 positioning the wipers of said switch opposite one group of lines, and means responsive to the dialing of another digit of a called number for releasing the wipers and for positioning the same opposite another group of 55 lines.

In witness whereof, I hereunto subscribe my name this 2d day of March, A. D. 1922.

JOHN E. GARDNER.
